UNITED STATES PATENT OFFICE.

JOHN J. NAVO, OF NEW ORLEANS, LOUISIANA.

DESIGN FOR A STAND FOR ARTICLES USED IN SEWING.

SPECIFICATION forming part of Design No. 37,105, dated August 23, 1904.

Application filed July 6, 1904. Serial No. 215,532. Term of patent 7 years.

To all whom it may concern:

Be it known that I, JOHN J. NAVO, a citizen of the United States, residing at New Orleans, in the parish of Orleans and State of Louisiana, have invented a new, original, and ornamental Design for Stands for Articles Used in Sewing, of which the following is a specification, reference being had to the accompanying drawing, forming part thereof.

10 The figure is a perspective view of a stand

for articles used in sewing, showing my new design.

What I claim as new, and desire to secure by Letters Patent, is—

The ornamental design for a stand for articles used in sewing, as shown.
